CHARLES WARWICK, OF VANCOUVER, BRITISH COLUMBIA, CANADA.

SHINGLE-DRYING MACHINE.

984,623.

Specification of Letters Patent. Patented Feb. 21, 1911.

Application filed September 15, 1909. Serial No. 517,902.

To all whom it may concern:

Be it known that I, CHARLES WARWICK, citizen of the Dominion of Canada, residing at Vancouver, in the Province of British Columbia, Canada, have invented a new and useful Shingle-Drying Machine, of which the following is a specification.

This invention relates to a machine for drying shingles and is designed to effect that object by the exposure of the individual shingles to the drying agency as they come from the saw and before they are bundled.

The present method of drying shingles in bundles in a steam heated kiln is inefficient in that it takes a considerable time for the heat to penetrate and the moisture to escape from a tightly bound bundle of shingles and the inner shingles are frequently insufficiently dried. The process is also costly owing to the large number of shingles that is required to stock the kiln for that length of time. There is also the risk of fire to which such drying kilns are very liable and which may destroy a large number of shingles and an expensive kiln.

My effort has therefore been directed to the provision of a means whereby the individual shingles as they come from the saw are exposed to a dry heat that will effectually evaporate the moisture from them. This object I attain by passing the shingles on an endless conveyer band or succession of such slowly through a chamber exposed to the dry heat of a furnace flue, means being provided to withdraw from the chamber the evaporate moisture from the drying shingles; care being taken to so support the shingles on the band that both sides of them are exposed to the action of the heat and to so arrange the conveyer bands, where more than one is used that in the earlier stages the heat is not sufficiently intense or sufficiently dry to warp the shingles and that they are turned when passing from one band onto the other.

The invention also comprises certain subsidiary features in the construction of the conveyer band or chain to prevent the feather edges of the shingles from catching in it and to a means for rectifying the shingles on the bands.

The invention is particularly described in the following specification, reference be-

ing made to the drawings with which it is accompanied, in which:

Figure 1 is a vertical longitudinal section through the drying chamber and its flues; Fig. 2, a sectional plan on the line A A in Fig. 1; Fig. 3, a vertical cross section on the line B B in Fig. 2; Figs. 4 and 5, end and side elevations of the overturning and centering guards at the receiving end of each band; Fig. 6, an enlarged detail of the conveyer band and a section of its driving reel and Fig. 7, a detail of the shaft and flanged wheels by which the conveyer bands are supported in the extended length between the end reels.

In these drawings 2 represents an elongated chamber preferably of thin sheet metal which chamber is exposed to dry heat by a flue 3 from a furnace, the flue 3 passing, in this particular machine, from the center of one side of the chamber 2 along the bottom of it and along one side to one end, along the other half of the bottom and the other side to the other end and back to an exit 4 adjacent to the point of entrance whence the flue is connected to a chimney or smoke stack. Partitions 5 and 6 separate this flue at the mid-length and along the bottom. This arrangement of the flue 3 is not, however, in any way essential to the invention as the same may be modified to suit the requirements. Within this flue-heated chamber 2 a series of endless conveyer bands 10 are carried on rotatably mounted reels 11 toward each end of the chamber by which reels at one or both ends the conveyer bands are driven at a uniform slow speed in opposite directions by sprocket wheels 12 external to the chamber or by other suitable means. These conveyer bands 10 are so arranged in relation to one another that the one above delivers onto the one beneath at a sufficient distance from the end to enable a shingle falling off one to be received by the other, and a guard 13 secured to and downwardly projecting and angled outward from the end of the chamber 2 prevents the falling shingle from passing down behind the reel 11. This guard 13 has angled sides 14 designed to center the shingle on the band which angled sides are carried forward from the guard as at 15.

As it is designed that the shingle falling

from one band onto the one beneath shall in that movement be turned over, the upper side of each band is a greater distance at the receiving end from the under side of the 5 one above it than at the delivery end, so as to afford more room for the shingles to turn over.

Difficulty has been experienced in designing a band that will have the required flexibility around the end reels, that will sustain the shingles off the general surface of the band that both ends may be exposed to the drying agency, that will not offer any interstices or apertures in which the feather 10 edges of the shingles are likely to catch, and that is withal simple and cheap to manufacture. With these objects in view I preferably construct the band as a chain of links 15 each formed of thin sheet metal of the required width of the conveyer, one end 17 being formed cylindrically to receive a shaft 18 the ends of which project beyond the width of the band to receive small flanged wheels or rollers 19 on each side to run on 20 longitudinal tracks 20 and support the band or chain between its ends. The other end 25 21 of each link is oppositely bent to encircle the smaller end 17 as shown in Figs. 6 and 7.

The driving and carrying reels 11 may 30 each be constructed of two flanges 25 across between which are secured bars 26 the pitch between which corresponds with the pitch of the chain links so that the bars 26 will engage the bent ends of the chain links and 35 effect the driving of the chain.

The shingles are delivered onto the band at a hopper 27 at one end of the top which 40 hopper is provided with sloped sides that will rectify and center the shingles on the width of the upper band 10, and the dried shingles are delivered at the opposite lower end through an aperture 28 onto a chute 29.

The moist vapor given off from the drying shingles is conducted from the chamber 45 2 through a passage 30 which may be connected with a chimney to induce a draft.

In use the shingles are fed through the hopper 27 and are centered on the upper band 10 traveling slowly in the direction of 50 the arrow toward the other end of the chamber 2. As they overbalance at that end the overbalancing end will fall upon the band 10 beneath, traveling in the opposite direction, being centered in its fall by the 55 angled sides 14 and 15 of the guard. The band beneath traveling in the opposite direction will carry the overbalanced end of the shingle under the band above until the after end of the shingle falls over in which movement the original under side is uppermost 60 and in the fall this end is again centered on the band. This reversal is effected at each end of the machine as the shingles are transferred from one band to the other until they

reach the exit 28 and are delivered onto the 65 chute 29 to be bundled. The speed of the conveyer band is so regulated that the time of exposure to the temperature of the chamber will effectually dry the shingles before they are delivered from the machine. 70

It will be noted that the upper part of the chamber 2 is not directly exposed to the heat of the flue and the shingles on the upper band are therefore only exposed to the hot air and moist vapors rising from the lower 75 part. This insures that the earlier process of drying is not conducted too rapidly, and toward the lower part of the chamber where a greater heat is necessary to effect the final drying the shingles are exposed to a greater 80 and a drier heat.

The heat admitted to the flues 3 may be controlled by a damper 31 in the entering flue.

Although I prefer the arrangement here 85 revealed of superposed conveyer bands delivering the shingles one upon the other, as such an arrangement is I believe a more favorable one and will economize space I do not desire to be confined to it as I regard the 90 essential feature of my invention to be the conveyance on a traveling band of the shingles through a flue-heated chamber.

Having now particularly described my invention and the manner of its construction 95 and use I hereby declare that what I claim as new and desire to be protected in by Letters Patent, is:

1. As a means for drying shingles, a furnace flue, a container set into said flue to 100 form a flue-heated chamber, a part of said container projecting above said flue, an inlet and outlet to said container, a plurality of sets of endless conveyers in said container, means for delivering the contents of the upper conveyer onto the upper side of the next lower conveyer, and means for imparting movement to said conveyers some of said conveyers being located in the projected part of said container above said flue and the 105 remaining conveyers being located in said container within said flue.

2. A means for drying shingles comprising a flue, a thin sheet metal casing or container inclosing a chamber and set into said 115 flue, a succession of endless conveyers mounted to move in opposite directions in said casing, angle guards depending from the ends and sides adjacent to the ends of said casing over the receiving end of each conveyer, end reels around which said conveyers pass, trackways in said casing, said conveyers having side projections for engaging said trackways, means for delivering shingles onto the upper band, means for delivering 120 shingles from the lower band and a moist vapor outlet for said casing.

3. As a means for drying shingles, the

combination with a flue, of a casing or container set into said flue with its upper portion projected out of said flue, endless conveyor bands in said casing, one above the other, the upper of said bands being mounted in the upper part of said casing above said flue.

In testimony whereof I have signed my name to this specification in the presence of two subscribing witnesses.

CHARLES WARWICK.
